UNITED STATES PATENT OFFICE.

JOHN G. HOLMES AND GEORGE PUFFER, OF WAUPUN, WISCONSIN.

VALVE-RESEATING DEVICE.

No. 876,964.

Specification of Letters Patent.

Patented Jan. 21, 1908.

Application filed November 15, 1906. Serial No. 343,630.

To all whom it may concern:

Be it known that we, JOHN G. HOLMES and GEORGE PUFFER, citizens of the United States, residing at Waupun, in the county of Fond du Lac and State of Wisconsin, have invented a new and useful Valve-Reseating Device, of which the following is a specification.

This invention relates to a device for reseating globe and gate valves without the necessity of disconnecting the valves from the pipe system, and it relates more particularly to a device for truing worn, irregular, or defective valve seats from time to time, until the stock at the seat becomes so cut away that further truing is impracticable, whereupon the entire seat is bored out and the opening tapped for receiving a bushing adapted to form a new valve seat.

The invention has for one of its objects to improve and simplify the construction and operation of devices of this character so as to facilitate the truing and renewal of valve seats in a simple, reliable and efficient manner.

A further object of the invention is to provide a reseating tool which is of simple construction and composed of few parts comparatively cheap to manufacture, and which is adapted to be used for reseating valves of different sizes, and which is designed to employ different forms of cutters necessary for truing and renewing the valve seats.

With these objects in view, and others, as will appear as the nature of the invention is better understood, the invention comprises the various novel features of construction and arrangement of parts, which will be more fully described hereinafter and set forth with particularity in the claims appended hereto.

In the accompanying drawing, which illustrates one of the embodiments of the invention, Figure 1 is a semi-longitudinal section and elevation of the device shown in the operation of truing a valve seat of a globe valve. Fig. 2 is a fragmentary elevation of the device in the operation of boring out an old valve seat for the reception of a bushing, the valve being shown as of the gate type. Fig. 3 is a perspective view of the lower end of the spindle and the tap for threading the bored out seat so as to receive the seat bushing. Fig. 4 is a perspective view of the seat bushing.

Corresponding parts in the several figures

are indicated throughout by similar characters of reference.

Referring to the drawing, 1 designates the spindle of the device which has a working fit in the tubular body 2 in which the spindle is mounted to simultaneously rotate and move longitudinally. The spindle 1 is of the same cross section throughout its length and provided with a collar 3 adjacent its upper end. The top extremity of the spindle is formed into a non-circular head 4 for the reception of a brace, wrench, or equivalent means, for rotating the spindle. The lower end of the spindle is reduced to form a shoulder 5 and is provided with a transverse passage 6 of rectangular cross section for receiving the truing tool or cutter 7, as shown in Fig. 1, or the boring cutter 8, as shown in Fig. 2. The cutters are held in place by a binding screw 9 which is threaded in the tapped opening 10 extending inwardly from the bottom end of the spindle to the passage 6. On the reduced portion 11, the tap 12 is adapted to fit, and the upper end of the tap is held against the shoulder 5 by the binding screw 13 engaging at its inner end in the socket 14 on the said reduced portion 11. By this arrangement, cutters and taps of different shapes and sizes may be separately used on a single spindle, so that the tool can be employed for various sizes and types of valves.

The lower end of the body 2 of the device is provided with an external screw thread 15 which is adapted to engage in the valve engaging portion, a threaded ring 16 being used in connection with small sized valves, as shown in Fig. 1, or in the yoke or bracket 17 for adapting the device to large size valves, as shown in Fig. 2. The ring 16 has an external thread 18 that is adapted to screw into the bonnet receiving opening of the valve casing, as shown, and several of such rings are provided so as to fit casings having bonnet receiving openings of different sizes. The yoke or bracket 17 is provided with a central tapped opening 19 which receives the threaded end 15 of the body 2 and on opposite sides of the opening are provided elongated slots 20 through which extend the screw bolts 21 for securely holding the yoke on the valve casing. At the upper end of the thread 15 the tubular body 2 is formed with an enlargement 22 constituting a shoulder arranged to bear on the supporting ring 16 or yoke 17. The

exterior of the body 2 is provided with a thread 23 which extends from the upper end to approximately the middle thereof, and the remaining surface is milled at 24, so as 5 to form a grip whereby the body can be screwed and unscrewed with relation to the supporting ring or bracket. Engaging the thread 23 is a sleeve 25 which forms a means for feeding the spindle 1. This sleeve is 10 constructed with an internal annular shoulder 26 which abuts the upper surface of the collar 3, so that the sleeve 25 causes the spindle to move downwardly as it screws on the tubular body 2. The exterior of the feed sleeve 25 15 at 27 is milled so as to afford a gripping surface whereby the sleeve can be turned by hand. In order to hold the collar 3 in engagement with the shoulder 26 and to prevent the falling of the spindle as well as to 20 permit positive feeding movements in both directions, a split clamping ring 28 encircles the spindle 1 at a point above the sleeve 25 and is held rigidly on the spindle by means of the screw 29 which draws the end of the 25 ring together. By means of the clamping ring and collar 3 engaging on opposite sides of the shouldered portion 26 of the feed sleeve, the spindle is held in place in the body 2, and prevented from free longitudinal 30 movement therein independently of the sleeve. By this construction, the several parts can be readily assembled and disassembled.

In the operation of truing a valve seat, the parts are assembled and positioned, as shown 35 in Fig. 1, with the cutter 7 secured to the spindle. This cutter is provided with a semi-circular cutting edge 30 to correspond with the normal contour of the valve seat. The cutting edge, however, will be varied for 40 different forms of valves. The spindle 1 is now rotated by a brace, or other suitable means, and the depth of the successive cuts is produced by imparting a partial turn to the feed sleeve 25 from time to time as the 45 spindle 1 is continuously rotated. In practice, a few turns on the spindle will be sufficient to properly dress the valve seat. After this is done, the device is removed from the valve casing and the bonnet with the valve 50 is replaced so as to be ready for regular operation. It will thus be seen that a valve can be reseated with comparatively little trouble. When the stock of the diaphragm 31 forming the seat 32 becomes too far cut away by 55 repeated reseating, the diaphragm is bored out by means of the tool 8 so as to form a cylindrical opening 33, as shown in Fig. 2. The tool is then taken out of the valve casing and

the cutter 8 removed so that the tap 12 can be placed on the spindle 1. The device is 60 then again placed on the valve casing and the opening 33 threaded by means of the tap. After the opening is threaded, the device is removed and the seat bushing 34 screwed into the tapped opening. This bushing is preferably made of brass or equivalent material and is exteriorly threaded to fit the opening 33, and on the interior are the lugs 35, which form means for engagement with a suitable instrument whereby the bushing can be 70 screwed in or out. After the bushing has been screwed into the proper position, the device is used with the cutter 7 for rounding off the top end of the bushing for the purpose of forming the seat. This bushing may be cut 75 down from time to time as the seat becomes worn, and, when required, a new bushing can be substituted. These bushings are of simple construction, and will be made of different diameters, so as to fit valves of various sizes. 80

We have described the principle of operation of the invention, together with the apparatus which we now consider to be the best embodiment thereof, but we desire to have it understood that the apparatus shown is 85 merely illustrative, and that various changes may be made, when desired, as are within the scope of the invention.

What is claimed is:—

In combination, a tool carrying spindle in 90 the form of a long cylindrical bar having an operating head and an annular flange and provided at its lower end with a reduced portion forming an annular shoulder, there being a tool receiving slot extending dia- 95 metrically of such reduced portion and the side and end of the reduced portion having openings for the passage of tool binding screws, a cylindrical body bored for the passage of the spindle and having externally 100 threaded upper and lower ends, a threaded sleeve fitting the upper threads of the body and having an inturned flange fitting over the flange of the spindle, and a collar clamped on the spindle above said inturned flange 105 whereby the spindle may be positively fed in both directions.

In testimony that we claim the foregoing as our own, we have hereto affixed our signatures in the presence of two witnesses.

JOHN G. HOLMES.
GEORGE PUFFER.
